LOCOMOTIVE SMOKE CONSUMER

Fred G. Stephens, Granite City, Ill.

Application September 15, 1932, Serial No. 633,259

5 Claims. (Cl. 110—76)

This invention relates to locomotive smoke consumers.

It is a familiar fact that, in the operation of locomotives using coal as fuel, difficulty is encountered in obtaining sufficiently complete combustion to prevent the discharge of large and objectionable amounts of smoke, soot and other products of imperfect combustion. A cause of the failure to obtain complete and sufficient combustion has existed in the insufficiency of the construction of the locomotive and in the combustion equipment thereof to inject a sufficient amount of oxygen into the combustion chamber and into the partially vaporized products of combustion to cause these products of combustion to be consumed and to prevent their discharge into the open atmosphere.

An object of the present invention is to provide construction and equipment that may easily be embodied in and combined with many or all types of railway and terminal locomotives now in general use in this country to inject into the combustion chamber of the locomotive an increased amount of air which becomes mixed with the gases resulting from incomplete combustion, and thereby supply the gases and the solids entrained therewith or supported thereby with sufficient oxygen to increase combustion thereof and prevent or diminish their discharge into the open atmosphere. In accomplishing this object of the invention, I have devised a satisfactory arrangement and construction easily capable of embodiment in and combination with many or most types of locomotives with which I am familiar, in order to obtain the indicated beneficial effects and results.

Another object of the present invention is to provide equipment for locomotives and the like easily capable of embodiment and combination therewith to utilize and cooperate with many of the existing elements and features of the locomotive in order to modify the operation and effects of the existing features, and to utilize their action to obtain nearly complete combustion of the gases and solids that have heretofore been discharged into the open atmosphere as a result of incomplete combustion.

Another object of the invention is to improve and increase greatly the efficiency of the combustion equipment of locomotives and the like, to utilize profitably the large proportions of fuels that have heretofore been lost and discharged into the open atmosphere, and to reduce the amount of fuels required to operate the locomo-

tives successfully and satisfactorily, and thereby diminish the cost of their operation.

Other objects will be apparent from the following description, reference being made to the annexed drawing, in which—

Fig. 1 is a vertical longitudinal sectional view of that portion of the locomotive comprising the fire-box and adjacent equipment.

Fig. 2 is a vertical cross-sectional view approximately on the line 2—2 of Fig. 1, but offset through one side wall to intersect the air inlet passage.

Fig. 3 is an enlarged cross-sectional view approximately on the line 3—3 of Fig. 1.

The body of the locomotive shown comprises a fire-box 1 into which the fuel coal is delivered through a door opening 2, the burning coal and heavy solid products of combustion being supported upon the grate structure 3. The arch tubes 4 have one end opening into the cellular water space 5 at the fuel receiving end of the fire-box. These tubes extend forwardly and downwardly and have their forward ends opening into the cellular water space 6 at the front lower portion of the fire-box. An arch 7 composed of fire-brick extends across the lower front portion of the fire-box between the side walls 8 thereof, and is supported by the tubes 4 and the walls 8. A space 9 is provided at the lower front end of the arch 7 through which a part of the products of combustion may pass beyond the arch to the flues 10, through which flues the products of combustion pass to ultimate discharge from the locomotive. The rear upper end of the arch 7 leaves a wide space 11 between said arch and the rear end of the fire-box, through which the remaining volatile products of combustion may pass to the flues 10.

The locomotive supports a main compressed air reservoir 12 which is kept filled with compressed air by operation of a pump 13 operating to pump air into the reservoir 12 and to compress the air in said reservoir to the extent desired through a pipe 14.

According to the present invention, I provide an auxiliary compressed air reservoir 15. I provide a pipe 16 opening into the pipe 14 and into one side of a pressure reducing valve device 17 which is effective to discharge the air from the opposite side thereof at reduced pressure into a pipe 18. I consider the Westinghouse feed reducing pressure valve adequate for this purpose because said valve is well known commercially and is used for the purpose of reducing the pressure of air admitted to one side and discharged

from the other side thereof, so that the construction, use and mode of operation of said valve are well known and require no detailed illustration or explanation herein.

- 5 The pipe 18 opens into the auxiliary reservoir 15, and the pressure reducing valve 17 is easily adjustable and operative to reduce the pressure from the high pressure in the reservoir 12 to a desired pressure of twenty to thirty pounds, for 10 instance, in the auxiliary reservoir 15. The pipe 16 is equipped with a valve 19 manually adjustable to vary the amount of air passing through the pipe 16, or to prevent any air from passing through said pipe from the pipe 14, as desired. 15 A pipe 20 has one end opening into the auxiliary reservoir 15 and the other end communicating with any appropriate known type of pressure gage 21 mounted in a convenient position for observation, as shown. 20 A pipe 22 has one end opening into the auxiliary reservoir 15 and the opposite end opening into a flue or tube 23 extending through the water space 24 at one side of the fire-box.

A fire-brick 25 forming a part of the arch 7 is 25 rigidly mounted between the wall 8 of the firebox and the adjacent arch tube 4, and has passage 26 therethrough with one end communicating and registering with the inner end of the flue 23, so that the compressed air discharged from 30 the pipe 22 will pass through the flue 23 and into and through the passage 26. A fire-brick 27 forming a part of the arch 7 has inwardly diverging passages 28 and 29 therein. The outer side edge of the fire-brick 27 that abuts against the 35 inner side edge of the fire-brick 25 has an opening formed by the intersection of the outwardly converging and inwardly diverging passages 28 and 29. Extended portions 30 and 31 of the passages 28 and 29, respectively, extend to the inner 40 side edge of the fire-brick 27 and communicate with passages 32 and 33, respectively, in an adjacent abutting fire-brick 34.

The passage 28 and the passage 32 have discharge openings 35 through which air is discharged to the underside of the arch 7, as clearly indicated by the broken lines 36 (Fig. 1). And the passages 29 and 33 have discharge openings 37 at their ends through which air is discharged above the arch 7, as clearly indicated by the 45 broken lines 38. The said fire-brick 25, 27 and 34 extend considerably above the arch forming fire-brick 7, so that the discharge openings 37 are 50 above the upper surface of the arch formed by said fire-brick 7 and will direct intersecting jets 55 of air upwardly and rearwardly into the space between the rear end of the arch and the upper wall of the fire-box.

The air jets 36 discharged through the openings 35 converge or intersect, as clearly shown in Fig. 1, 60 thus producing an agitated whirling effect of the gases and entrained solids and obtaining an adequate mixture of air therewith, with the result that a far better and more complete combustion is obtained, thus preventing a great 65 amount of the volatile matter and entrained solids from passing to the flues 10.

Similarly, the jets of air 38 discharged from the jet openings 37 intersect each other and inject a sufficient amount of air, and thereby supply sufficient oxygen, to cause a nearly complete combustion of the remaining volatile and entrained solid fuels produced by the incomplete combustion of the coal.

75 My invention comprises means for varying and regulating the amount of air discharged into the

fire-box in accordance with the requirements. It is known that more air is required on some occasions than on others. In order to vary and regulate the amount of air to obtain the desired results, the pipe 22 is equipped with a valve 39 located in a position convenient for operation by the fireman. Thus the amount of air discharged into the fire-box by this invention can be controlled in accordance with needs.

I am aware that this invention and its arrangement, in combination with known types of locomotives, may be varied as required to adapt the invention to said different types, all without departure from the nature and principle of the invention. I do not restrict myself in unessential particulars, but what I claim and desire to secure by Letters Patent is:—

1. In a locomotive having a firebox, and a series of fire-brick forming an upwardly and rearwardly inclined arch in the firebox, certain of said fire-brick toward the front of said arch having portions extending above rearwardly adjacent fire-brick and having passages opening through the rear of said upwardly extended portions for ejecting jets of air above the arch into and toward the rear of the firebox.

2. In a locomotive having a firebox, a series of fire-brick forming an upwardly and rearwardly inclined arch in the firebox, certain of said brick toward the front of the arch having transverse passages extending toward one side wall of the firebox and having openings at their rearward faces both above and below said arch and directed toward the rear of the firebox, and means forming a passage through the side wall of the firebox for discharging fluid into said passages in said fire-brick.

3. In a locomotive having a firebox provided with a grate structure in the lower portion thereof and with a fuel delivery door through the rear end thereof and having walls forming a water space at the rear lower portion of said firebox and also having flues opening from the front of said firebox; an arch of fire brick extending upwardly and rearwardly from the front lower portion of said firebox and having a space near its front lower portion for the passage of products of combustion from said firebox against one of said walls and toward said flues and the rear end of said arch being separated by an intervening space from the rear end and top of the firebox for the passage of a part of the products of combustion from the firebox toward said flues, said arch having passages therethrough for ejecting converging jets of air below said arch and toward the rear of the firebox and having other passages for ejecting converging jets of air above said arch and toward the rear of the firebox, and mechanism for forcing air through all of said passages and into the firebox.

4. In a locomotive having a firebox, and a series of fire-brick forming an upwardly and rearwardly inclined arch in the firebox provided with an opening at its forward lower portion for the passage of a part of the products of combustion and said arch having its rear end separated by an intervening space from the rear end and top of the firebox for the passage of products of combustion, certain of said fire-brick toward the front of said arch and rearwardly from said opening having portions extending above rearwardly adjacent fire-brick and having passages opening through the rear of said upwardly extending portions for ejecting jets of air above

said arch into and toward the rear of said firebox.

5. In a locomotive having a firebox, a series of fire-brick forming an upwardly and rearwardly inclined arch in the firebox provided with an opening at its forward lower portion for the passage of a part of the products of combustion and said arch having its rear end separated by an intervening space from the rear end and top of

10 the firebox for the passage of products of com-

bustion, certain of said fire-brick toward the front of the arch and rearwardly from said opening having transverse passages extending toward one side wall of the firebox and having openings at their rearward faces both above and below said arch and directed toward the rear of the firebox, and means forming a passage through the side wall of the firebox for discharging fluid into said passages in said fire-brick. 5

FRED G. STEPHENS. 10
